US00D558617S

(12) **United States Design Patent** (10) **Patent No.:** **US D558,617 S**
Hill et al. (45) **Date of Patent:** **** Jan. 1, 2008**

(54) **REMOTE ELECTRICAL TIMER**

(75) Inventors: **Ambreese S. Hill**, Jacksonville, FL (US); **Robert Schultz**, Memphis, TN (US); **Nicole Ashley Moody**, Memphis, TN (US)

(73) Assignee: **Hunter Fan Company**, Memphis, TN (US)

(**) Term: **14 Years**

(21) Appl. No.: **29/277,747**

(22) Filed: **Mar. 8, 2007**

(51) **LOC (8) Cl.** **10-03**

(52) **U.S. Cl.** **D10/40**

(58) **Field of Classification Search** ..... D10/40, D10/106; D13/138.1, 137.1, 137.3, 139.8, D13/139.6, 162, 162.1; 368/97-100, 107, 368/110-113; 307/141, 141.4; 439/650-653; 200/33 R, 38 R

(57) **CLAIM**

The ornamental design for a remote electrical timer, as shown and described.

DESCRIPTION

FIG. 1 is a perspective view of a remote electrical timer showing our new design.

FIG. 2 is a bottom plan view thereof.

FIG. 3 is a top plan view thereof.

FIG. 4 is a right side view thereof.

FIG. 5 is a left side view thereof.

FIG. 6 is a front view thereof; and,

FIG. 7 is a rear view thereof.

The broken lines in the views show environmental features which are for illustrative purposes only and form no part of the claimed design.
